UNITED STATES PATENT OFFICE.

DAVID H. DARLING, JR., OF RYE, NEW YORK, ASSIGNOR TO THE UNITED STATES BATTERY COMPANY, OF NEW YORK, N. Y.

DESIGN FOR A BATTERY-CELL.

SPECIFICATION forming part of Design No. 33,181, dated August 28, 1900.

Application filed July 19, 1900. Serial No. 24,230. Term of patent 14 years.

To all whom it may concern:

Be it known that I, DAVID H. DARLING, Jr., a citizen of the United States, residing at Rye, county of Westchester, and State of New

5 York, have invented and produced a new and original Design for Battery-Cells, of which the following is a specification, reference being had to the accompanying drawings, forming a part thereof.

10 Figure 1 is a side elevational view of a battery-cell showing my design, and Fig. 2 is a plan view thereof, as seen looking at Fig. 1 from the top toward the bottom of the drawings.

15 As shown in the drawings, the leading or material feature of my design consists of a

cylindrical battery-cell A, having an enlarged reverse cone-shaped portion B and a second cylindrical portion D, C being the top, to which are secured posts E E.

20

Having described my invention, what I claim as new, and desire to secure by Letters Patent, is—

25 The design for a battery-cell, as herein shown and described.

In testimony whereof I have signed my name to this specification in the presence of two subscribing witnesses.

DAVID H. DARLING, JR.
